PAIR OF BINOCULARS

Kurt Jensen, Wetzlar (Lahn), Germany, assignor to Ernst Leitz Gesellschaft mit beschränkter Haftung, Wetzlar (Lahn), Germany

Filed Dec. 8, 1961, Ser. No. 67,842

Term of patent 14 years

(Cl. D57—1)

Fig. 1

I claim:

The ornamental design for a pair of binoculars, as shown.
